Primary Examiner — Patricia Palasik*(74) Attorney, Agent, or Firm* — Eckert Seamans Cherin & Mellott, LLC; Grant E. Coffield; John P. Powers(57) **CLAIM**

The ornamental design for a vacuum port, as shown and described.

DESCRIPTION

FIG. 1 is an isometric view of a vacuum port in accordance with an embodiment of the invention;

FIG. 2 is a bottom isometric view of the vacuum port of FIG. 1;

FIG. 3 is a top view of the vacuum port of FIG. 1;

FIG. 4 is a right view of the vacuum port of FIG. 1;

FIG. 5 is a bottom view of the vacuum port of FIG. 1;

FIG. 6 is a front view of the vacuum port of FIG. 1;

FIG. 7 is a back view of the vacuum port of FIG. 1; and,

FIG. 8 is a section view taken along line 8-8 of FIG. 6.

The portions shown in broken lines are for illustrative purposes only and do not form a part of the claimed design. The left side elevational view (not shown) of the vacuum port is a mirror image of the right side elevational view.
